ATTORNEY.

UNITED STATES PATENT OFFICE.

CHESTER A. YOUNG, OF ST. JOSEPH, MISSOURI.

DESIGN FOR AN EDUCATIONAL CHART.

60,844.

Specification for Design.

Patented Apr. 11, 1922.

Application filed October 29, 1921. Serial No. 511,535. Term of patent 14 years.

To all whom it may concern:

Be it known that I, CHESTER A. YOUNG, a citizen of the United States, residing at St. Joseph, in the county of Buchanan and State of Missouri, have invented a new, original, and ornamental Design for an Educational Chart, of which the following is a specification, reference being had to

the accompanying drawing, forming part thereof.

The figure is a view in plan of an educational chart embodying my design.

I claim:

The ornamental design for an educational chart as shown.

CHESTER A. YOUNG.
